Inventor.

UNITED STATES PATENT OFFICE.

JOHN THOMSON, OF BROOKLYN, NEW YORK, ASSIGNOR TO MARIA T. BARTON, OF SAME PLACE.

DIFFERENTIAL REGISTER.

SPECIFICATION forming part of Letters Patent No. 274,674, dated March 27, 1883.

Application filed August 28, 1882. (No model.)

To all whom it may concern:

Be it known that I, JOHN THOMSON, a citizen of the United States, residing at Brooklyn, county of Kings, and State of New York, have invented new and useful Improvements 5 in Differential Registers, of which the following is a specification.

The object of my invention is to provide an apparatus adapted to effect registration for all 10 purposes, and for use in all places in which registers are employed, said apparatus being cheap and simple in construction, and affording a reliable register which can be easily read, and which shall indicate the highest desired 15 reading for any purpose.

To this end my invention consists in a toothed dial-wheel rotating under a fixed indicator by which the unitary notation is effected, a follower-wheel rotating upon the 20 same axis, but differentially toothed, and carrying an indicator-hand over the dial, which registers sums of one hundred units, and a third indicator, also carried over the said dial, actuated by a disk rotating with the follower- 25 wheel, and having a single notch into which a pawl carried by said follower-wheel falls each time the dial gains one complete rotation upon the follower-wheel, and advances said disk one tooth before it is withdrawn from engagement therewith, whereby sums of ten thousand 30 units each are registered.

My invention finally consists in several details of construction, which will be fully described hereinafter, and then pointed out in 35 the claims.

Referring to the drawings, Figure 1 is a front elevation. Fig. 2 is a side elevation. Fig. 3 is a detail view of the follower-wheel, with the blind-wheel and ratchet-wheel with 40 pawl. Fig. 4 is a detail view of the dial-wheel, with modified devices for imparting movement thereto. Fig. 5 is a central section of Fig. 1, the parts being enlarged and broken off at top and bottom. Fig. 6 is a central transverse 45 section of Fig. 3.

In the construction of this apparatus, 1 is a dial-wheel provided with a graduated annulus which has one hundred equal graduations marked thereon. The periphery of said dial-wheel is provided with one hundred teeth of

equal pitch, which are adapted to engage with a worm, 3, mounted in bearings 19 and 20; so that it may be revolved freely and thereby impart a slow and regular rotation to the dial-wheel. The latter is supported upon a central 55 shaft or stud bearing, 13, and rotates beneath a fixed hand or pointer, 4, by which registration from 1 to 99 is indicated.

Behind the dial-wheel, and supported by the same bearing, but having upon its periphery 60 one hundred and one teeth of equal pitch with the teeth on wheel 1, is the follower-wheel 2, both of which mesh with the worm 3. Now, it is evident that if the worm-shaft 3 is rotated—as, for instance, by a ratchet and pawl—it will 65 rotate the dial-wheel 1 and the follower-wheel 2 in the same direction; but as the follower-wheel has one more tooth than the dial-wheel it is plain that as both are turned by the same worm the dial will gain upon the follower one 70 tooth in each revolution. Thus the dial will, by passing under the hand 4, toward the left hand of Fig. 1, register one with said hand for each turn of the worm, and after one hundred turns of said worm 3 it will stand at the zero-point, 75 as indicated by said Fig. 1 of the drawings; but in the same time the follower-wheel 2 has been rotated by the same worm, but at each revolution thereof the dial gains upon it by the space of one tooth, during a single revolution of the said dial.

By reference to Fig. 5 it will be seen that the follower-wheel 2 is mounted rigidly upon a sleeve, 12, on the bearing 13, and to the outer end of said sleeve is secured a hand or pointer, 6, which travels with said sleeve. The dial moves under this hand, and as the former gains a single tooth upon the follower 2 it will be seen that in a single revolution of the dial the hand 6 will be removed one unit's space 85 toward the right on the graduate. This hand registers sums of one hundred, and will therefore, in connection with the indicator 4, register up to and including ninety-nine such sums, together with ninety-nine units registered by 90 the hand 4; or, in other words, a sum of nine thousand nine hundred and ninety-nine units, which is their utmost limit. The next step is to advance these readings by separate indications of ten thousand units each. To effect 95

register-readings from ten thousand up to one million, or in that vicinity, ordinarily requires considerable and complicated mechanism; but by my invention this is accomplished in the following manner. The mechanism is as follows:

To the inside of the dial-wheel is secured a disk or blind-wheel, 7, in the periphery of which is formed a single notch, 8, both dial and blind-wheel being secured together to turn as one. Between this blind-wheel and the follower-wheel 2 is placed a spring-washer, 9, and a ratchet-wheel, 10, is placed between it and the follower 2. The periphery of the ratchet 10 is divided into one hundred equal teeth, and the wheel itself is slightly less in diameter than the blind-wheel, as seen in Fig. 2. This ratchet-wheel is rigidly mounted upon a sleeve, 11, which rotates upon the sleeve 12, as shown in Fig. 5, and upon the outer extremity of said sleeve is mounted rigidly a hand or pointer, 14, turning with said sleeve and ratchet-wheel. As the dial-wheel and blind-wheel rotate upon but not with the sleeve 11, the spring-washer 9 tends to keep them apart from the ratchet-wheel, and also creates sufficient frictional resistance to prevent movement upon the part of the ratchet-wheel, except as it is actuated by the mechanism.

Upon the inside face of the follower-wheel 2 is pivoted a pawl, 15, actuated by a light spring, which turns it down. The point of this pawl rides upon the periphery of the blind-wheel 7, which is of somewhat greater diameter than the ratchet-wheel 10. Now, it will be remembered that the consequence of the differential movement of the dial and the follower-wheel is that for each revolution of the dial it gains one-hundredth part of a revolution on the follower 2, and it will therefore require ninety-nine rotations of the dial-wheel before the pawl 15 will reach the notch 8 in the blind-wheel. The hand 14 meantime travels with the dial undisturbed; but at the ninety-ninth revolution the pawl will reach the notch, will be sprung down into it, and thereby into engagement with a tooth in the ratchet-wheel 10, and during the one hundredth revolution it will give the said ratchet, and thereby the hand 14, a relative movement of one one-hundredth of a revolution, at the end of which the pawl 15 will be drawn out of engagement with the ratchet-wheel 10 by riding up on the inclined edge of the notch 8. During its engagement it will have caused the hand 14 to register a single space upon the graduate; but as said hand registers only sums of ten thousand units each this space will indicate such a registration. The pawl will not again engage with the notch 8 until a second series of ninety-nine revolutions of the dial 1 have been accomplished, when the operation just described will be repeated, and a second sum of ten thousand will be registered, and this may be continued until the registration reaches a final sum of nine hundred and ninety-nine thousand nine hundred and ninety-nine units.

The method of forming the dial is shown in Fig. 6. The dial-wheel, which is stamped out by a die, is also made with an annular recess, 70 16, stamped or otherwise formed in its face. I then print, stamp, or mark in any suitable manner the necessary graduations upon an annulus of such dimensions as to exactly fill the recess in the dial-wheel. This annulus is 75 formed of any suitable material—such as paper, celluloid, rubber, &c.—and is inserted and secured within the recess, the proper relative position thereof being indicated by a register point stamped on the wheel and printed on the 80 annular dial. This forms a cheap but perfect dial flush with the face of the wheel, thereby permitting the hands to lie close to the graduations, thereby reducing the liability of error in reading.

Should it be desired (as it frequently is) to reset all the hands at zero, this may be readily effected by loosening the screw 17, when the slot 18 of worm-bearing 19 and the pivoted bearing 20 will permit the worm to be withdrawn from mesh with the wheels 1 and 2, when the hands 6 and 14 and the dial (the latter with relation to the stationary hand 4) may be instantly reset, as required, after which the worm may be reset to engage, as before.

The blind-wheel 7, though shown as separate and distinct, may be stamped in the dial-wheel 1, and the notch formed therein in a manner analogous to that shown and described for forming the recess 16 for holding the dial-graduate. By such a construction the whole number of wheels would be reduced to three.

The worm 3 is thought to be the construction best adapted for meters where a number of strokes may be required to register a single 105 volume. The proper rotation of the screw would then be determined by the ratchet-connection to the worm, which latter forms no necessary part of my invention, and is not therefore shown; but where a single stroke 110 should be correspondingly registered by an indication of one unit on the dial, I substitute for the worm a direct pawl-connection, such as that shown in Fig. 4. Said pawl is shown at 21, and is mounted upon a vibrating lever 115 or pivoted pawl-carrier, 22, pivoted upon the same center on which the dial revolves. In this form of construction a safety-pawl, 23, may also be pivoted to the base 5. The operation in this instance is the same as that already 120 described, except that each movement of the lever 22 causes an indication of one upon the dial. The machine is also simplified thereby.

Of course the proportions herein given may be changed to suit varying purposes. For example, the dial might be made to read 10, 500, or 1,000, instead of 100.

In my invention all the parts may be made of stamped metal, the work of assembling the register being very simple, in consequence of 130 the arrangement of the small number and simplicity of the parts.

Having thus described my invention, what I claim is—

1. A register indicating measurements of units and sums of units, said indication being effected for single units by a rotating dial passing under a fixed hand, as to sums of one hundred units each by a hand rotating over said disk, but retarded by a differentially-toothed wheel meshing with the same motor as the dial, and as to sums of ten thousand units each by a hand actuated by a ratchet and pawl, the latter carried by the differentially-toothed wheel and the former by the dial-wheel, or a wheel rotating with it and provided with a single notch, said pawl being held out of engagement with said ratchet until it reaches the notch, substantially as described. 15
2. The combination, with the rotating dial, of the differentially-toothed follower-wheel, the ratchet-wheel interposed between a blind-wheel or equivalent device, having a single 20 notch and rotating with said dial, next the
- ratchet, and a pawl pivoted to the follower-wheel and riding upon the periphery of the blind-wheel, substantially as described.
3. The combination, with the ratchet-wheel, of a spring-washer interposed between the same 25 and the blind-wheel or dial, substantially as described.
4. The combination, with the follower-wheel, of the blind-wheel having a single notch with inclined edge, the ratchet-wheel, and the pawl 30 pivoted to the follower-wheel, substantially as described.
- In testimony whereof I have hereunto set my hand in the presence of two subscribing witnesses.

JOHN THOMSON.
